(57) **CLAIM**

The ornamental design for the rechargeable carpet sweeper, as shown and described.

DESCRIPTION

FIG. 1 is a perspective view of the rechargeable carpet sweeper showing my new design;

FIG. 2 is a front view of the rechargeable carpet sweeper;

FIG. 3 is a right side view of the rechargeable carpet sweeper, the left side view being a mirror image thereof; and,

FIG. 4 is a top view of the rechargeable carpet sweeper.

The bottom portion of the rechargeable carpet sweeper forms no part of the claimed design.
